UNITED STATES PATENT OFFICE.

LEO STEIN, OF ROCHESTER, NEW YORK.

DESIGN FOR A BURIAL-CASKET.

SPECIFICATION forming part of Design No. 20,491, dated January 27, 1891.

Application filed April 22, 1889. Serial No. 308,213. Term of patent 14 years.

To all whom it may concern:

Be it known that I, LEO STEIN, a citizen of the United States, residing at Rochester, in the county of Monroe and State of New York, 5 have invented and produced a new and original Design for Burial-Caskets, of which the following is a specification, reference being had to the accompanying drawings, forming part thereof.

10 Figure 1 is an elevation of the detached end of a burial-casket, showing my design. Fig. 2 is a sectional view of the same, these two figures being deemed necessary to fully illustrate my design.

15 The leading feature of my design consists in a casket having on its side a depressed panel A, a raised top bar a, projecting beyond the plane of the panel B and having its outer face formed by horizontally-extending con- 20 cavo-convex and inclined planes, a lower bar at the base of the panel having its outer face formed with horizontally-extending concavo-convex and concave surfaces, and raised columns B, projecting beyond the plane of the 25 panel and within the plane of the upper cross-bar a.

A denotes the depressed panel of the coffin, which consists of a plane surface. At the top of the panel A is the top bar or molding a, 30 having beads at its top and bottom edge, with concavo-convex and inclined surfaces between the two beads.

b represents the lower bar at the base of the panel A, the outer face of which is formed with a top and bottom bead and with a con- 35 cavo-convex and concave surface between the two beads.

B represents the columns raised above the plane of the panel A, with their upper extremity depressed within the plane of the bar 40 a. The central portion of the column is flat and formed with a series of depressed panels or grooves and the extremities with a series of inclined planes. This peculiar arrangement of surfaces of different contour ar- 45 ranged in planes one within the other produces a very desirable effect and renders the design very pleasing.

Having thus fully described my invention, what I claim as new, and desire to secure by 50 Letters Patent, is—

The design for burial-caskets, substantially as herein shown and described.

In testimony whereof I have hereunto signed my name, in the presence of two at- 55 testing witnesses, at Rochester, in the county of Monroe, in the State of New York, this 29th day of March, 1889.

LEO STEIN.
